TOY BANK

Irving Rosenbloom, Great Neck, N. Y., assignor to
Renwal Manufacturing Co., Inc., Mineola, N. Y.,
a corporation of New York

Application August 28, 1951, Serial No. 243,949

4 Claims. (Cl. 46—4)

1

This invention relates to a toy bank. An object of this invention is to provide a toy bank having the simulated appearance of the entry portion of an actual bank, including a simulation of the revolving doors commonly found in bank entrances, such simulated revolving door being operative to effect the deposit of a coin into a coin receiving portion of the bank.

Another object of this invention is to provide in a toy bank of the character described, a hollow base formed with coin insertion and removal slots, the simulated revolving door having mounted thereon a simulated figure of a messenger carrying a bag or grip, such bag or grip having a pair of coin receiving fingers for vertically positioning a coin on the base, the door being adapted to be manually revolved to bring the positioned coin into registry with the coin insertion slot to permit such coin to drop through the slot into the hollow base, a closure means being mounted on the base to close the coin removal slot therein and adapted to be moved to allow removal of coins collected in the hollow base.

Other objects of this invention will in part be obvious and in part hereinafter pointed out.

The invention accordingly consists in the combination of elements and arrangement of parts as exemplified in the herein described embodiment thereof.

In the drawing, Fig. 1 is a front elevational view of a toy bank embodying the invention; Fig. 2 is a top plan view thereof; Fig. 3 is a vertical section taken on the line 3—3 of Fig. 1; Fig. 4 is a horizontal section taken on the line 4—4 of Fig. 3; Fig. 5 is a horizontal section taken on the line 5—5 of Fig. 3; Fig. 6 is a vertical section taken on the line 6—6 of Fig. 5; Fig. 7 and Fig. 8 are elevational views of parts of the revolving door; Fig. 9 is a top plan view of the door; Fig. 10 is a horizontal section taken on the line 10—10 of Fig. 7 and Fig. 11 is a vertical section taken on the line 11—11 of Fig. 8.

Referring in detail to the drawing, 10 designates a toy bank embodying the invention which comprises a simulated entrance to an actual bank, designated as 11. A revolving door 12 is mounted in the entrance for rotation about a vertical axis with a simulated figure 13 of a messenger carrying a bag or grip 14, mounted in one of the quadrants of the door.

The entrance 11, which may be formed of molded plastic components, includes a hollow base member 15 of circular outline. The base

2

includes an upper or top wall 16 which is formed with a coin receiving slot 17, a central opening 18 and a peripheral slot 19. Extending from the forward portion of member 15 is a semi-circular stepped portion 20 formed with radial slots 21 at the ends thereof. A lower or bottom wall 22 closes off the bottom of member 15; such wall being formed with a coin removal slot 23 and a pair of oppositely disposed, flanged, guide and closure plate retainer members 24 located on the inner surface thereof. A substantially rectangular closure plate 25 is slidably mounted on the inner surface of wall 22 with the lateral edges thereof engaged by guide retaining members 24. The plate 25 includes a down turned flange 26 at the forward end thereof for limiting the inward movement of the plate and an upstanding pin 27 adapted to engage stepped portion 20 to limit the outward movement of the plate. Mounted on top wall 16 is an upstanding semi-circular side wall 28 provided with downwardly extending tabs 29, 30 receivable in slots 21, 19 respectively in member 15. The side wall 28 is closed at the top by a horizontal substantially semi-circular wall 31 which is formed with an opening 32 which is aligned with opening 18 in wall 16. An upstanding, molded strip 33 is located at the forward edge of wall 31 and carries indicia spelling out "bank."

The simulated revolving door 12 comprises a pair of flat, rectangular-shaped members 34, 35 having rectangular openings therein. Member 34 is formed with a vertical slot 36 located on the mid portion thereof and extending downwardly from the upper edge thereof to a central point thereof and with a short vertical bearing pin 37 which is receivable in central opening 18 in wall 16. A pair of parallel lugs 38 are located on the lower edge portion of member 34 and provide a space therebetween which is aligned with slot 36. Similarly, member 35 is formed with a vertical slot 39 on a mid portion thereof and extending upwardly from the lower edge thereof to a central point. Member 35 also includes a centrally located, upstanding pin 40 receivable in opening 32 in wall 31 and a pair of parallel lugs 41 located on the upper edge portion of member 35 which provide a space therebetween which is aligned with slot 39. The lugs 38, 41 are located on opposite sides of the members 34, 35 respectively.

The door 12 is formed by assembling members 34, 35 with the slotted portions thereof interfitting and the edge portions of each member adjacent the slot thereof being received be-

tween the lugs on the other member, to provide a firm interconnection between the assembled members.

The figure 13 which may be molded of plastic material or the like, includes on the outer surface of bag or grip portion 14 thereof, a pair of horizontally disposed coin positioning fingers 42. The fingers 42 are spaced from bag portion 14 to allow a coin to be loosely placed between the fingers and the outer surface of the bag portion. Extending laterally from the bag portion 14 are ears 43 which are received in recesses 44 formed in adjacent portions of members 34, 35 at the lower portions thereof, thus positioning the figure 13 in one of the quadrants of door 12. A stud 45 extending from the rear of figure 13 which is engageable with a corner portion of the door 12 and horizontally disposed, spaced lugs 46 on the lower edges of members 34, 35 which receive a rearwardly extending flange on figure 13, properly position the figure in the quadrant of the door.

With figure 13 properly positioned on door 12, which in turn is rotatably mounted on the base 15 with pins 37 and 40 received in the aligned openings 18 and 32 in walls 16, 31 respectively, the tabs 29, 30 may be inserted in the slots 19, 21 on wall 16 and cemented therein, to assemble the parts of the device. The bottom wall 22 carrying the closure plate, is cemented to the bottom of base 15, to complete the assembly.

Upon placing a coin such as a penny, dime or quarter within coin fingers 42 on bag portion 14 of the figure 13, the same is positioned vertically on wall 16. The door 12 is rotated by means of pin 40 which projects above wall 31 or by directly pushing the door. The fingers 42 are so located, as to allow the positioned coin to move over wall 16 and to register with the coin insertion slot 17 therein, thus allowing the coin to fall through the slot into the interior of hollow member 15. The coins collected within member 15 are readily removed therefrom by pulling the closure plate 25 forwardly to expose the coin removal slot 23. Ribs 47 on the inner surface of plate 25 act as a coin slide to prevent coins from jamming against pin 27.

To further increase the simulation of an actual bank, the inner surface of side wall 28 may be covered with a pictorial representation of bank tellers, cages and the like, as by adhering a decal or the like thereto.

It is understood that door 12 may be rotated in either direction to bring a positioned coin over slot 17. The entire effect of the bank is heightened by placing the coin as though it was being carried in the bag or grip 14.

It will thus be seen that there is provided a toy bank in which the several objects of the invention are achieved and which is well adapted to meet the conditions of practical use.

5 As various possible embodiments might be made of the invention herein described and as various changes might be made in the embodiment above described, it is to be understood that all matter herein set forth or shown in the accompanying drawing it is to be interpreted as illustrative and not in a limiting sense.

Having thus described my invention, I claim as new and desire to protect by Letters Patent:

15 1. A toy bank comprising a hollow base including upper and lower walls parallel to each other, said upper wall being formed with a coin insertion slot and said lower wall being formed with a coin removal slot, closure means slidably mounted on said lower wall for closing said coin removal slot, a semicircular side wall mounted on said upper wall in upstanding position, a top wall on said side wall parallel to said upper wall, a pair of crossed members simulating a revolving door mounted on said upper and top walls for rotation about a vertical axis, a figure simulating an individual mounted in an upstanding position between adjacent portions of said crossed members, said figure including a pair of laterally extending fingers spaced above said upper wall and adapted to position a coin supported by said upper wall, said door being adapted to be rotated to a position wherein said positioned coin will fall through said coin insertion slot.

20 2. A toy bank as in claim 1, and further including on the interior of said side wall representations of tellers in a bank.

25 3. A toy bank as in claim 1, wherein each of said crossed members is formed with a vertically extending slot on a median portion thereof whereby said members may be interengaged substantially at right angles to each other.

30 4. A toy bank as in claim 3, wherein adjacent portions of said crossed members are formed with recesses and said figure is formed with ears receivable in said recesses.

IRVING ROSENBLUM.
